SHIPPING CONTAINER FOR MICROSCOPIC
SLIDES OR THE LIKENils Kristian Johan Christiansen, 20 Vesterbrogade,
1620 Copenhagen, Denmark

Filed Mar. 10, 1971, Ser. No. 123,117

Claims priority, application Denmark Dec. 23, 1970

Term of patent 14 years

Int. Cl. D3—02

U.S. Cl. D87—1 D

FIG. 1 is a perspective view of a shipping container for microscopic slides or the like showing my new design in an open position; and

FIG. 2 is a perspective view thereof in a closed position, the side opposite that seen being plain and unornamented.

I claim:

The ornamental design for a shipping container for microscopic slides or the like, as shown and described.
